UNITED STATES PATENT OFFICE.

ANDREW J. PIERCE, OF RACINE, WISCONSIN.

GAS-ENGINE.

SPECIFICATION forming part of Letters Patent No. 564,643, dated July 28, 1896.

Application filed June 7, 1893. Serial No. 476,900. (No model.)

To all whom it may concern:

Be it known that I, ANDREW J. PIERCE, of Racine, in the county of Racine and State of Wisconsin, have invented certain new and useful Improvements in Gas-Engines; and I do hereby declare that the following is a full, clear, and exact description thereof, reference being had to the accompanying drawings, forming part of this specification.

10 My invention relates to gas-engines, and will be fully described hereinafter.

In the drawings, Figure 1 is a longitudinal section of a cylinder embodying my invention. Fig. 2 is a section on line 2 2, Fig. 1.

15 Fig. 3 is an elevation. Fig. 4 is a section showing a modification.

A is the cylinder of a gas-engine, and B is the piston. C is an electrode, which, by a set-bolt *a*, is clamped to the vertical arm of an 20 angle-lever *b*, which lever is hinged to an arm *c* of a plug *d*, that passes down through a bushing of insulated material *e* in the end of the cylinder.

25 The plug *d* is hollow, and its head rests on bushing *e*, while its lower end is screw-threaded to receive a nut *d'*, and through the plug is passed a rod or plunger *D*, having a collar *D'* at its upper end that fits loosely in a countersink in the plug. The extreme upper end 30 of the rod or plunger *D* projects through a slot in the horizontal arm *b'*.

The rod or plunger *D* may be packed in the plug, as at *f*, and a spring *f'*, one end of which is attached to the nut *d* and the other 35 to the rod or plunger *D* and serves to support the latter to keep the electrode in place.

By the construction above described I am 40 enabled to use a rigid electrode, which does not depend on its temper for proper action, as the spring that keeps it up to its work is entirely outside of the cylinder.

The plug *d* is connected to battery by wire *x*, and the electrode *C* may be used either in 45 connection with an electrode *E*, that is operated by the crank of the engine, as will be described hereinafter, or with an electrode on the piston, as shown in Fig. 4.

Figs. 1, 2, and 3 show the upper electrode as operated by the crank of the engine.

50 A rock-shaft *G* passes through bearings *g g* in the upper portion of the combustion-chamber *A'*, and on its projecting end is provided

with an arm *G'*, while at its center it has keyed to it a clamp *H*, which holds the upper electrode *E*.

55

The arm *G'* has a slotted connection with a horizontal rod *I*, which has bearings *h h'* in the engine-frame, and an antifriction-head, which is held against the face of the cam *K* by a spring *i*. The cam *K* is carried by a 60 gear-wheel *L*, and this meshes with a pinion *M* on the engine-shaft *m*. The rod *I* carries an insulated contact-point *O*, that is wired to battery, as shown in Fig. 3, and a lug *O'* projects from the engine-frame in the path 65 of the point *O*.

The pinion and gear-wheels are timed with each other so as to give the cam any desired number of revolutions, say, in this instance, the gear-wheel and its cam revolve once to 70 each two revolutions of the pinion. Now imagine the cam *K* to be revolving in the direction indicated by the arrow, thus exposing its reduced periphery to the head of rod *I*, and permitting the rod to be thrust out by the 75 spring. Then the arm *G* will oscillate its shaft and bring the two electrodes *C E* into and out of contact, producing a spark, for when the contact-points *O O'* touch and a circuit is established, then as the cam continues 80 to revolve, its thicker portion reaching the head of rod *I*, forces it back, but without moving arm *G'*, owing to the slotted connection between the two, until after the rod has carried its contact-point *O* clear of that of *O'* 85 on the engine-frame, and hence at this stroke no explosion will take place, and the fly-wheel (not shown) will make one stroke of the piston.

In Fig. 4 the moving electrode *E* is carried 90 directly by the piston, and the action of the device is obvious.

The plunger *D* is headed and fitted loosely in the countersink, that the internal gas-pressure may keep it closed against leakage.

95

Having thus fully described my invention, what I claim as new, and desire to secure by Letters Patent, is—

1. In a gas-engine, the combination with a cylinder, having an igniting-chamber thereon, and a piston, of a movable electrode in the chamber, means for moving the same a stationary electrode, a clamp member supporting the same, an insulated sleeve passing

100

through the walls of the chamber a hinged connection between the clamp member and sleeve, a spring-pressed rod D extending through the sleeve and loosely engaging the clamp member, a metallic circuit, and means for closing the same, substantially as described.

- 5 2. In a gas-engine, the combination with a cylinder and its piston, of a stationary electrode, a movable electrode, a rock-shaft on which the latter is mounted, a crank-arm on the shaft, a gear mechanism actuated by the

piston, a cam driven by said mechanism, a spring-actuated rod having one end in engagement with the cam, and a sliding connection 15 at its opposite end with the crank-arm, a fixed contact, a contact carried by said spring-actuated rod, and a circuit connection between the stationary electrode and the contact on the rod, substantially as described.

ANDREW J. PIERCE.
